UNITED STATES PATENT OFFICE.

WILLIAM M. BRUCE, JR., OF SPRINGFIELD, OHIO.

TELEGRAPHY.

Application filed April 28, 1920. Serial No. 377,302.

To all whom it may concern:

Be it known that I, WILLIAM M. BRUCE, Jr., a citizen of the United States, residing at Springfield, in the county of Clark and 5 State of Ohio, have invented certain new and useful Improvements in Telegraphy, of which the following is a specification.

My invention relates to improvements in telegraphy and particularly to the method 10 and apparatus for transmitting and receiving signals over submarine cables.

The object of the invention is particularly to increase the speeds in sending and receiving such cable signals.

15 In the ordinary recording type of signal on submarine cables impulses of opposite polarity are employed for transmitting the characters such as dots and dashes. The number of such impulses which can be transmitted over submarine cables and other lines 20 of high capacity is limited by the characteristics of the conductor. In sending signals in the continental code the average number of such impulses for each letter is approximately four. These signals when received 25 by an ordinary recorder are indicated by markings on a moving tape above and below an imaginary line, the duration of the impulses and the character of the impulses being the same. In other words, the time limit required to make a dot or dash is the same and consequently if it requires an average of 30 four impulses for each letter four time elements or units of time are required on an average for each letter transmitted.

35 In my improved method I employ means for transmitting and receiving impulses of different polarity and also of different characteristics of the same polarity by varying the current, preferably by varying the voltage of the current for the impulses of different polarities. Thus, if I use a negative impulse of a certain voltage and another negative impulse of a different voltage and the same as to the positive impulses, I employ 40 means which will transmit these impulses into signals of different characters so that they not only have the impulses resulting from the different polarities but also different characters of impulses of the same polarity. Inasmuch as the time element of these 45 respective impulses will be the same whether of one voltage or the other and inasmuch as these different characteristics of marking 50 when received can be developed into a code

in which we will say for instance a short marking and a long marking would be used for each impulse of each polarity, assuming that we have two characteristics for each polarity, the time element is reduced to practically one-half of that required to send signals where the impulses of opposite polarity have all the same characteristics. If we had three or more characteristics for each polarity, the time element would be correspondingly reduced and the speed of sending correspondingly increased.

55 In the accompanying drawings I have illustrated diagrammatically apparatus necessary to send and receive signals in accordance with this invention.

In these drawings:—

Fig. 1 is a diagrammatic view of the sending apparatus.

Fig. 2 is a similar view of the receiving 75 apparatus.

Fig. 3 shows the manner in which the signals might be recorded.

80 In Fig. 1, *a* represents a conductor such as a submarine cable having the artificial lines *a*¹ and condensers *a*² and *a*³ of the usual type for duplex operation. In the system as illustrated I employ four circuit closers *b*, *b*¹, *b*², *b*³ which may be similar to the ordinary sending keys now employed except there are 85 two for positive and two for negative impulses. In practice, however, these would be contacting devices arranged on an automatic sender. For each of these circuit closers there is a relay (*c*, *c*¹, *c*² and *c*³) adapted 90 to be operated from a local battery *d* when the circuit closers are operated to close the circuits. These relays each have armatures *e*, *e*¹, *e*² and *e*³, normally resting on a back contact but adapted when the relay is operated to move to a forward contact. The negative side of the main cable battery *d*¹ is 95 connected directly to the armature *e* of relay *c* through wire 1 and to the armature *e*² of relay *c*² through the wire 2. The positive side of the cable battery is connected to the back contact of the armature *e*¹ of relay *c*¹ by wire 3 and to the back contact of armature *e*³ of relay *c*³ by wire 4. The armature *e*¹ of relay *c*¹ is connected to the cable 100 or conductor through wire 5 and the armature *e*³ of relay *c*³ is connected to earth by wire 6; the conductor or cable being thus normally grounded or earthed through wire 5, armature *e*¹, and its back contact, wires 105

3 and 4 and the back contact on armature e^3 and the said armature and through wire 6 to ground.

The circuit closers b , b^1 , b^2 , b^3 , are each connected to one end of the coil of each of the relays c , c^1 , c^2 , c^3 by wires 7, 8, 9 and 10, the opposite ends of each of these relay coils being connected by the common wire 11 to one side of the battery d , the opposite side of the battery d being connected by the common wire 12 to contacts b^4 , b^5 , b^6 and b^7 for these circuit closers.

The forward contacts e^4 and e^5 of relays c and c^2 are connected by wires 13 and 14 to the wires 8 and 10 respectively leading from the circuit closers to the relays c^1 and c^3 and the armatures e and e^2 of these relays are connected to the battery wire 12 by wires 15 and 16 so that when the armatures of relay c and c^2 are pulled up they close the circuit through the relays c^1 and c^3 and cause these relays also to be operated as will hereinafter more fully appear.

The forward contacts e^6 and e^7 of relays c^1 and c^3 are connected through resistance r^1 and r^2 to wires 1 and 2 which lead to opposite sides of the main cable battery d^1 , and the back contacts e^8 and e^9 of relay c and c^2 are connected by wires 17 and 18 to one side of the respective resistances r^1 and r^2 so that with the wire 1, armature e , back contact e^8 and wire 17 a shunt is established around the resistance r^1 , and with wire 2, armature e^2 , back contact e^9 and wire 18 a similar shunt is established around the resistance r^2 .

With this explanation assume that the circuit closer b is operated against the contact b^4 which will establish a circuit from the battery d through wire 12, contact b^4 , circuit breaker b , wire 7 to relay c thence by the common battery return wire to the other side of the battery d . This will energize the relay c causing its armature e to move to the forward contact e^4 thus breaking the shunt around the resistance r^1 at the contact e^8 . As the armature e moves against the contact e^4 a circuit is established from battery d through wires 12 and 15, armature e , contact e^4 , wire 13 to relay c^1 , thence through common battery wire 11 to the other side of battery d , thus operating the relay c^1 and causing its armature e^1 to move to the forward contact e^6 . This armature e^1 is connected directly to the cable by the wire 5, consequently the negative side of the battery will be connected to the cable through the wire 1, resistance r^1 , contact b^6 , relay c^1 and wire 5, while the opposite side of the battery will be connected through wire 4, armature e^3 and wire 6 to earth, thus sending a negative impulse into the cable. As soon as this circuit is broken at b^4 by the operation of the circuit breaker b the armatures e and e^1 will drop back to their back contacts,

earthing the cable through the circuit heretofore described. If the circuit closer b^1 should be operated a circuit would be established through wire 12, contact b^5 , circuit breaker b^1 , wire 8 to relay c^1 and by the common battery wire 11 to battery thus operating the relay c^1 . This will cause the armature e^1 to contact with its forward contact e^6 and inasmuch as the relay c in this case is not operated a circuit will be established from the conductor through wire 5, armature e^1 , contact e^6 , wire 17, back contact c^8 , armature e , wire 1 to negative side of the battery while the positive side of the battery remains earthed through the wire 4, armature e^3 and wire 6. This results in another negative impulse being impressed upon the cable but inasmuch as the relay c has not been operated the resistance r^1 will be shunted and an impulse of different potential but of the same sign will be impressed upon the cable.

If the circuit breaker b^2 should be operated circuits will be established from battery d through contact b^6 , circuit closer b^2 , wire 9, relay c^2 , and battery wire 11, thus operating the relay c^2 . This results in breaking the shunt for the resistance r^2 at the contact e^9 , establishing a circuit from the battery d through wires 12 and 16, armature e^2 , forward contact e^5 , wire 14 to relay c^3 and by common battery wire 11 to the other side of the battery, hence both relays c^2 and c^3 are operated. The armature e^2 of c^2 breaks the shunt around the resistance r^2 and the armature e^3 , contacting with the forward contact e^7 , places earth on the negative side of the battery wire 6, armature e^3 through resistance r^2 and wire 2, while the positive side of the battery will be connected through wire 3, armature e^1 and wire 5 to the cable; thus a positive impulse is imparted to the cable through the resistance r^2 . When the circuit breaker b^3 is closed relay c^3 will be operated from battery d through wire 12, contact b^7 , circuit breaker b^3 , wire 10 and battery wire 11. In this case the relay c^2 is not operated and the shunt around the resistance r^2 is closed at contact 9. The negative side of the battery, however, will be connected to earth as before through wire 2, armature e^2 , contact e^9 , wire 18, contact e^7 , armature e^3 , and wire 6 to ground, while the positive side of the battery will be connected to the cable through wire 3, armature e^1 and wire 5 as before; thus a positive impulse of higher potential will be imparted to the cable than when the resistance r^2 is in circuit. Means are thus provided for sending into the cable impulses of opposite polarity but of different potential. In Fig. 2 the means for translating these impulses is illustrated. The cable or conductor a provided with the usual receiving circuits has connected thereto a re-

ceiving relay f in the nature of a galvanometer having a movable coil f^1 connected by the wires f^2 and f^3 across the line in the usual manner. This movable coil f^1 is provided with a mirror on which there is reflected a beam of light from a lamp L through suitable lenses which in turn is reflected and normally stands in a neutral zone marked O between two sets of sensitive elements such as selenium s , s^1 , s^2 and s^3 . Each of these elements is connected to the primary of a transformer t , t^1 , t^2 and t^3 . The elements being connected by wire 20 to primary p of the transformer t . s^1 is connected by wire 21 to the primary p^1 of transformer t^1 , s^2 by wire 22 to primary p^2 of transformer t^2 , and s^3 by wire 23, primary p^3 of transformer t^3 . The secondaries y , y^1 , y^2 and y^3 of these respective transformers are connected to relays g , g^1 , g^2 and g^3 preferably of the movable coil type. The movable coil of each of the said relays is in circuit with the primary of one of the respective transformers. For each transformer t , t^1 , t^2 and t^3 there is provided a local relay h , h^1 , h^2 and h^3 and a battery d^2 , d^3 , d^4 and d^5 . The tongue n of relay g is connected by wire 24 to battery d^2 from the other side of the battery to the coil of relay h and thence by wire 28 to the contact h^1 . The tongue h^1 of relay g^1 is connected by wire 25 to battery d^3 , the other side of which is connected to relay h^1 and by wire 29 to contact h^5 . The tongue h^2 of relay g^2 is connected by wire 26 to the battery d^4 , the other side of which is connected through relay h^2 and by wire 30 to contact h^6 . The tongue h^3 of relay g^3 is connected by wire 27 to battery d^5 , thence through relay h^3 , and wire 31 to contact h^7 , so that whenever either one of the relays g , g^1 , g^2 , or g^3 is operated the tongue of said relay closes the local circuit through a battery d^2 , d^3 , d^4 or d^5 and thus operates the corresponding relay h , h^1 , h^2 or h^3 . The armatures l , l^1 , l^2 and l^3 are connected by the common wire 32 and branches 33, 34 and 35 to a translating device M which may be of the ordinary recorder type, the opposite side being connected by wire 36^a to the center of a split battery d^6 , the positive side of this battery being connected by wire 36 and the branch wire 37 to the forward contacts l^5 and l^6 of relay h^2 and h^3 and the negative side of the battery being connected by wire 38 and branch 39 to the forward contacts l^7 and l^8 of relays h and h^1 . The branch wires 33 and 34 leading from the armatures l^1 and l^2 of relays h^1 and h^2 are provided with resistance r^3 and r^4 , the result of which is that when the relay h is operated the contact and its armature l^7 closes a circuit through wire 38, negative battery, wire 36, recorder M , and wire 32 to armature l , thus operating the relay or recorder M to its negative position and causes it to move to a distance determined by the potential of the battery. When the relay h^1 is operated a circuit is closed from contact l^8 through branch 39, wire 38, negative battery, wire 36^a, recorder M and branch 33 to armature l^1 and through the resistance r^3 which causes the recorder to move in the same direction but with a less potential and consequently to a less degree because of the resistance r^3 . The same result will occur when the relays h^2 or h^3 are operated with the exception that the operation of the relay h^2 will close the circuit contact l^5 through wire 36 and positive battery 36^a to recorder M and through resistance r^4 and branch 34 to armature l^2 thus causing the relay or recorder to move in the opposite direction but with a shorter movement by reason of the resistance r^4 . The operation of the relay h^3 will close a circuit from contact at l^6 through branch wire 37, wire 36, positive battery, wire 36^a, recorder M , wire 32, branch 35, and armature l^3 , thus operating the recorder in a positive direction but through a circuit without resistance and consequently to a movement determined by the battery potential.

Having thus described my invention, I claim:—

1. In a system of telegraphing, means for supplying to a conductor impulses of opposite polarity of a given potential and separate means for supplying to said conductor increased potential in phase with said impulses of opposite polarity in connection with a movable coil relay at a receiving station adapted to move in opposite direction by the current reversals and close a circuit to one set of translating devices in response to said reversals and move to a greater distance in either direction in response to the current impulse of increased potential and close another circuit to operate a different set of translating devices by the additional movement.
2. In a system of telegraphing, receiving mechanism embodying a plurality of sets of translating devices, and a relay adapted to move in either direction in response to current reversals of one potential and to control circuits to operate one set of translating devices, and to move to a greater distance in response to current impulses of increased potential and operate another set of translating devices.
3. In a telegraph system, means for supplying current reversals of one potential, additional means for supplying increased potential in phase with the current reversals, and a receiving relay, and translating devices operated thereby, one of said translating devices being adapted to be operated by the relay in response to the movement of said relay by the current reversals and the other to be operated by an increased

- movement of said relay in response to the increased potential.
4. In a telegraph system, receiving mechanism embodying a plurality of translating devices, and a relay moving in either direction in response to current reversals of one potential and operate one of said translating devices and to move to a greater distance in response to current impulses of an increased potential to operate another translating device, and a recorder controlled by said translating devices to record the movements of both of said translating devices.
- 15 5. In a telegraph system, a battery, means for sending reversals of current from said battery to a conductor through resistance, separate means for shunting said resistance in phase with said reversals to increase the potential of said positive or negative impulses, and a receiving relay operated by said reversals of one potential to operate one translating device and by said reversals of increased potential to operate a different translating device.
- 20 6. In a telegraph system for high capacity lines, a receiving device moved in opposite directions by current impulses of opposite polarity of one potential and moved to a greater degree in each direction by current reversals of increased potential, a plurality of elements operated by the different movements of said receiving device, one set of elements operated by a limited movement 25 of said receiving device in response to current reversals of one potential and another set by the increased movement of said receiving device in response to reversals of increased potential.
7. In a telegraph system for high capacity lines, a transmitter for sending current reversals through resistance to a conductor, means in said transmitter for shunting said resistance in phase with said reversals to increase the potential of certain positive and negative impulses, and a movable coil receiver having a plurality of circuit controlling elements and separate translating devices in said circuits, one set of said elements operated by the movement of the receiver in response to current reversals of one potential, and another set by reversals of increased potential.
8. In a telegraph system, a transmitter for sending current reversals of one potential into a conductor and means in said transmitter for increasing the potential of certain reversals in phase therewith, a receiving device moved to a limited extent in opposite directions by said current reversals of one potential and to a greater extent by reversals of increased potential, separate translating devices in circuit with light effected resistance elements, and means on said receiver to transmit light to said resistance elements to one set by the limited movement of said receiver, and to another set by the increased movement of said receiver, and thus operate the different translating devices one in response to reversals of one potential and the other in response to reversals of increased potential.
- 60 In testimony whereof, I have hereunto set my hand this 23rd day of April, 1920.

WILLIAM M. BRUCE, JR.
